AUTOMOBILE GRILLE BAR

Henry T. King and Harold W. Pilkey, Detroit,
Mich., assignors to Chrysler Corporation, Highland Park, Mich., a corporation of Delaware

Application May 12, 1953, Serial No. 24,969

Term of patent 7 years

(Cl. D14—18)

To all whom it may concern:

Be it known that we, Henry T. King and Harold W. Pilkey, citizens of the United States, residing in the city of Detroit, county of Wayne, and State of Michigan, have invented a new, original, and ornamental Design for an Automobile Grille Bar, of which the following is a specification, reference being had to the accompanying drawings, forming part thereof, in which:

Fig. 1 is a front elevational view of a portion of an automobile grille bar, showing our new design;

Fig. 2 is a plan view thereof;

Figs. 3 and 4 are sectional views taken on the lines 3—3 and 4—4 respectively of Fig. 1;

Fig. 5 is a sectional view taken on the line 5—5 of Fig. 2; and

Fig. 6 is a perspective view of an automobile grille bar wherein the broken lines indicating an automobile are for illustrative purposes only.

We claim:

The ornamental design for an automobile grille bar, substantially as shown and described.
